(57) **CLAIM**

The ornamental design for a lens cover assembly, as shown and described.

DESCRIPTION

FIG. 1 is an exploded isometric view of a lens cover assembly showing our new design, the lens cover assembly comprising a body portion (on the right of FIG. 1) and a removable cover (on the left of FIG. 1);
FIG. 2 is an assembled isometric view of the lens cover assembly shown in FIG. 1;
FIG. 3 is an isometric view of the body portion of the lens cover assembly shown in FIG. 1;
FIG. 4 is another isometric view of the body portion of the lens cover assembly shown in FIG. 1;
FIG. 5 is a front elevational view of the body portion of the lens cover assembly shown in FIG. 1;
FIG. 6 is a top plan view of the body portion of the lens cover assembly shown in FIG. 1;
FIG. 7 is a rear elevational view of the body portion of the lens cover assembly shown in FIG. 1;
FIG. 8 is a bottom plan view of the body portion of the lens cover assembly shown in FIG. 1;
FIG. 9 is a right side elevational view of the body portion of the lens cover assembly shown in FIG. 1;
FIG. 10 is a left side elevational view of the body portion of the lens cover assembly shown in FIG. 1;
FIG. 11 is an isometric view of the removable cover of the lens cover assembly shown in FIG. 1;
FIG. 12 is another isometric view of the removable cover of the lens cover assembly shown in FIG. 1;
FIG. 13 is a front elevational view of the removable cover of the lens cover assembly shown in FIG. 1;
FIG. 14 is a top plan view of the removable cover of the lens cover assembly shown in FIG. 1;
FIG. 15 is a rear elevational view of the removable cover of the lens cover assembly shown in FIG. 1;
FIG. 16 is a bottom plan view of the removable cover of the lens cover assembly shown in FIG. 1;
FIG. 17 is a right side elevational view of the removable cover of the lens cover assembly shown in FIG. 1; and,
FIG. 18 is a left side elevational view of the removable cover of the lens cover assembly shown in FIG. 1.
The broken lines shown in the Figures are included for the purpose of illustrating portions of the lens cover assembly that form no part of the claimed design.
